UNITED STATES PATENT AND TRADEMARK OFFICE
CERTIFICATE OF CORRECTION

PATENT NO. : D937,470 S
APPLICATION NO. : 35/510013
DATED : November 30, 2021
INVENTOR(S) : Vincent Van Duysen

Page 1 of 1

It is certified that error appears in the above-identified patent and that said Letters Patent is hereby corrected as shown below:

On the Title Page

At item (72), inventor's address should be corrected from "Valencia (ES)" to --Ribarroja (ES)--.

Signed and Sealed this
Fifteenth Day of August, 2023

Katherine Kelly Vidal
